[57] CLAIM

The ornamental design for a combined display and demonstration unit for lenses or the like, as shown and described.

DESCRIPTION

FIG. 1 is a perspective view of a combined display and demonstration unit for lenses or the like embodying my new design.

FIG. 2 is a front elevational view.

FIG. 3 is a top view taken along line 3—3 of FIG. 4.

FIG. 4 is a side elevational view.

FIG. 5 is a back elevational view.
